IRON-FREE ALUM

William S. Wilson, Boston, Mass., assignor to
Merrimac Chemical Company, Inc., Everett,
Mass., a corporation of Massachusetts

Application May 11, 1932, Serial No. 610,734

14 Claims. (Cl. 23—118)

This invention relates to the removal of iron salts from solutions of alum (aluminum sulfate) whereby an "iron free" alum is obtained, and it has application to the process of Semper and 5 Fahlberg, described in British Patent 5,579 of 1881 which involves the use of lead peroxide.

Ordinary commercial alum is manufactured from bauxite (aluminum hydrate) and sulfuric acid. The product contains a small amount of 10 iron which is reduced to the ferrous state during the process of manufacture; and is practically free from ferric iron. It consists approximately of 17.3% Al_2O_3 ; about .7% Al_2O_3 being in excess of the SO_3 equivalent. This grade of 15 alum is used extensively in the manufacture of paper sizing, water filtration, dyeing, tanning, purification of glycerine, etc. The product seldom contains more than .45% of iron as Fe_2O_3 .

The term "iron free" alum as now employed 20 in the art designates an alum which contains substantially less iron than the ordinary commercial grade, the amount thereof not exceeding .002% as Fe_2O_3 . This grade of alum finds use in the sizing of fine book or ledger papers, 25 in the manufacture of paper coat, dry colors, in tanning white leather, and in various dyeing operations. Inasmuch as bauxite of a grade which will give an iron free alum does not exist it is necessary to employ pure aluminum hydrate the cost of which is approximately three 30 times that of the cost per unit of Al_2O_3 . Accordingly, a process for removing the iron from ordinary alum is needed.

Although many such processes have been suggested, none have found commercial application. 35 In this connection, note should be made of the fact that many processes will reduce the amount of iron in alum. However, if a process is incapable of producing an alum having .002% Fe_2O_3 or less, it is worthless since commercial alums having relatively high or low iron contents command the same market price.

The principal object of this invention is to 40 provide a method of removing iron and analogous impurities, effectively, from alum solutions whereby a product having any desired maximum iron content can be obtained.

A further object of the invention is to afford 45 a method which enables one to remove the iron from alum without loss of any of the alum.

An additional object of the invention is to provide 50 an effective lead peroxide reagent as well as a method of regenerating the same.

A further object of the invention is to provide 55 a counter-current process for the removal of

iron whereby good yields of iron free alum are obtainable with but small quantities of the deferruginating agent. The invention likewise contemplates a method of treating alum solutions whereby the iron therein is rendered readily susceptible to the peroxide treatment. 5

According to the Semper-Fahlberg process, a concentrated alum solution, which is neutral or at least should not contain a large excess of acid, is mixed with 5%—20% (based on the 10 weight of the alum) of lead peroxide. Ferric plumbate is said to form, which is separated from the alum solution by permitting the same to settle, and thereafter decanting the clear liquid, or by filtering the suspension. 15

I have observed that the reaction appears to 20 involve an adsorption phenomenon rather than the formation of a ferric plumbate. Thus, for example, an iron containing alum solution which has been brought into equilibrium with a quantity of lead peroxide will contain some iron notwithstanding the fact that there is a very large stoichiometric excess of lead peroxide, assuming that ferric plumbate is formed. However, by 25 adding an additional quantity of lead peroxide, and agitating the suspension in order to bring about a state of equilibrium, the resulting alum solution will be found to contain less iron than before, thus indicating that the extent of the deferrugination is a function of the quantity 30 of the lead peroxide added. If, on the other hand, a solution of iron free alum be added to the suspended peroxide which is in equilibrium with the iron containing alum solution, some of the iron which has been adsorbed by the peroxide 35 will be returned to the solution.

Briefly stated, the present invention contemplates the preparation of a lead peroxide from red lead and nitric acid. After repeated washing, the peroxide so formed is added to an iron 40 containing alum solution which has previously been treated with a partially spent peroxide. The concentration of the solution is not important, although solutions in excess of 30° Bé. impede settling materially. After the peroxide has 45 been agitated in the alum solution thoroughly and is allowed to settle, the solution is decanted and a subsequent charge of alum solution is introduced into the tank which contains a higher percentage of iron than the previous charge. 50 After the removal of the iron has advanced to the desired extent, the solution of alum is evaporated to the desired concentration in the usual manner. The spent peroxide is washed substantially free from alum solution and thereafter 55

revivified by repeated treatment with acid, preferably sulfuric, containing progressively less iron. The removal of the iron from the spent lead peroxide appears likewise to involve an adsorption phenomenon, and it is, therefore, advantageous to remove the iron by a series of counter-current acid treatments, each successive acid wash having less iron than the next preceding until in the final treatment fresh acid is employed. The number of treatments may, of course, be varied, in general the greater the number of treatments, the less acid is required. Inasmuch as the peroxide settles rapidly from the acid solution, a large number of treatments are possible during a relatively short period of time as compared to the settling operations in the alum treatment. After the revivification is completed, the lead peroxide is used again, the alum solution first treated therewith being one which has reached its last stage of deferrugination.

The accompanying drawing illustrates diagrammatically one method of procedure wherein the alum solution is subjected to three stages of deferrugination. Fig. 1 is a flow sheet illustrating the process. Fig. 2 is a curve illustrating the process.

The details of the process are described hereinafter more fully.

30. Preparation of alum solution

The crude alum solution which is employed should be as concentrated as possible in order to obtain a maximum output of product per unit volume of capacity. On the other hand, a solution which is so concentrated that its viscosity is appreciable impedes sedimentation of the lead peroxide to such an extent as to prolong the cycle of operation thereby likewise reducing the capacity. In general, I found that a solution of basic alum of 30° Bé. concentration is about as strong as can be settled expeditiously.

Ordinary crude alum contains approximately 45.5% Fe_2O_3 . In order to assure that the iron is completely oxidized, a small quantity of sodium chlorate or sodium hypochlorite, or similar oxidizing agents are added to the alum in the course of its preparation, preferably just after the reaction between the bauxite and sulfuric acid.

Iron containing alum, particularly when dissolved in water, ages, that is, undergoes a change which is usually accompanied by a brown coloration. This change appears to be due to a change in the condition or form of the iron salt. In its changed condition, the iron salt is absorbed by the peroxide inefficiently. The change takes place rather slowly and it is possible under ordinary conditions to complete the removal of the iron before the non-absorbable form is produced. However, from time to time delays are incurred which have an adverse effect so far as the alum solution is concerned because of the formation of the relatively non-absorbable iron salt. This form can again be converted to the absorbable form by heating the solution (to a temperature which need not attain its boiling point), and thereafter cooling the solution. This simple procedure seems to reverse the aging process so far as the iron salts are concerned, and renders them readily susceptible again to the action of lead peroxide.

75 Adsorption of the iron may be effected at ordinary room temperature. However, I have ob-

served that slightly elevated temperatures are preferable. A temperature above 50° C. should be avoided notwithstanding the fact that sedimentation is more rapid at the elevated temperatures, since the lead peroxide tends to decompose, particularly if even small amounts of organic matter are present. Temperatures between 30° and 50° C. and preferably approximately 40° C. have given the most satisfactory results.

10. Preparation of lead peroxide

Lead peroxide may be made by various methods. In general, I have found that lead peroxides made in an alkaline medium are distinctly 15 inferior to those made in an acid medium. By far the best results have been obtained with lead peroxide which has been prepared by reacting red lead at room temperature with nitric acid of a concentration which will give a lead nitrate 20 solution which is nearly saturated. Various factors affect the quality of the peroxide product. For example, the peroxide deteriorates rapidly in dilute nitrate solution and in water. I have found, however, that the deterioration may be 25 prevented if the lead peroxide is stored in a spent condition, that is, one that is charged or has adsorbed on its surface a ferric salt. Before using the peroxide it must be revivified in the manner described more fully in a subsequent 30 portion of this specification.

Other sources of lead peroxide than that from red lead and nitric acid may be employed. Similarly, the lead peroxide may be charged with an iron salt and revivified regardless of the method by which the peroxide has been made. It is to be noted that because the process as a whole is one involving an adsorption phenomenon, the physical characteristics of the peroxide are important. Moreover, I have found that some 40 grades of red lead result in a lead peroxide which is of a better quality than others. The most practical method of determining the quality of red lead which I have found is to make a small sample of peroxide and check its action 45 on an alum solution containing a standard amount of iron.

60. Revivification of peroxide

The spent peroxide is revivified by first washing the peroxide free of alum solution. This may be done conveniently by washing the same repeatedly with water. The dilute alum solution which results may be used to dissolve crude alum or may be concentrated and returned to an appropriate stage of the deferruginating cycle. Thereafter the peroxide is treated successively with dilute aqueous sulfuric acid solutions. For this purpose a 4%-10% solution will be found to be satisfactory.

Inasmuch as the removal of the iron appears to involve an adsorption phenomenon, it is convenient and advantageous to treat the peroxide progressively with acid solutions containing successively less dissolved iron salts. The acid solution which is decanted from the peroxide after the first treatment may be discarded or preferably returned to the crude alum process where it is reacted with bauxite to produce the ordinary commercial grade of alum.

In general, the revivification involves agitating the peroxide with the solution of acid, permitting the peroxide to settle and decanting or otherwise separating the solution from the solid peroxide. Inasmuch as the settling operation is 75

rapid, it is convenient and economical to employ relatively small amounts of acid and subject the peroxide to a number of such successive treatments. Obviously, if desired, one may employ relatively large amounts of acid and thereby reduce the number of treatments. However, this increases the consumption of acid employed in the revivification.

The number of successive acid treatments depend upon the quantity of acid employed. I have found that from 5 to 10 treatments are practical. Following the last treatment, the peroxide is washed with water to remove the remaining acid, after which it is ready for use in the treatment of alum solutions. Inasmuch as the revivified peroxide deteriorates with age, insofar as its adsorption property is concerned, it is advisable to employ it promptly after revivification.

Deferruginating cycle

The removal of the iron from the alum solution involves, preferably, successive treatments of alum solutions with peroxide containing successively less iron. In other words, the crude alum solution moves counter-currently with respect to the revivified peroxide. The peroxide which is employed in the first treatment of the alum solution is most highly charged with iron, whereas the peroxide employed in the final treatment of the alum solution is the freshly revivified material.

A better understanding of the procedure involved may be had by reference to the accompanying diagram.

The diagram illustrates the cycle of operation which has been found suitable in treating alum containing approximately .5% Fe_2O_3 . A solution of 25°-30° Bé. concentration is prepared in the manner previously described, suitable precautions have been taken to assure the presence of all of the iron in a ferric state.

A solution of this type respond to a three stage deferruginating cycle, each stage requiring approximately 24 hours. It is convenient under these conditions to employ five tanks (A, B, C, D, and E) of approximately equal capacity. At the beginning of the first day, tank A may be assumed to contain an alum solution which is in its last stage of deferrugination. Tank B contains an alum solution which is starting its intermediate or second day of deferrugination. Tank C contains fresh or crude alum solution. Tanks D and E are idle although they may be used for revivification purposes, if desired. For this purpose, tank D would contain peroxide which is to be washed free of alum and thereafter subjected to the early stages of revivification, whereas tank E contains peroxide undergoing the later stage of revivification and washing operation preparatory for deferrugination.

The alum solutions contained in tanks A, B, and C are agitated thoroughly in order to obtain a uniform suspension of the peroxide and thereby establish an adsorption equilibrium between the iron in the solution and the iron adsorbed on the peroxide. This period of agitation varies although one to two hours will, in general, be found to be adequate. Equilibrium itself is practically instantaneous once the suspension is completed. Thereafter the agitation is discontinued and the peroxide is permitted to settle at the bottom of the tank.

At the end of the first day, the supernatant liquid contained in tank B is siphoned or pumped into tank E where it is admixed with the freshly

revivified peroxide in pursuance of the final stage of deferrugination. The supernatant liquid in tank A is completely deferruginated, and is siphoned or pumped into a suitable storage tank or evaporating kettle, wherein the water is removed and the iron free alum product produced, and the supernatant liquid in tank C is transmitted to tank A. Following these transfers, the alum solutions in tanks A, B and E are agitated thoroughly whereby an intimate mixture of the peroxide is obtained and an equilibrium between the iron in solution and the iron absorbed is established. The process of sedimentation is then initiated.

Depending upon the quantity of peroxide employed as well as the extent of sedimentation, tank C will contain a certain amount of partially deferruginated alum after the decantation operation. This alum solution is recovered by repeated addition of water and decantation or siphonation of the supernatant liquid. Alternatively, one may discharge the deposit consisting of peroxide and alum solution, and filter the liquid phase, and thereafter wash the solid product. The solution so obtained may be employed advantageously in preparing subsequent batches of crude alum solution. After the peroxide is essentially free of alum solution, it is subjected to revivification. In the meantime, the peroxide which has undergone the first stages of washing and revivification of tank D is subjected to continued revivification preparatory for its use during the third day in the deferruginating cycle. Following the second day, alum solution contained in tank E is decanted or pumped to the iron free solution storage. The supernatant liquid in tank B is pumped into tank E and the supernatant liquid in tank A is pumped into tank D, which contains freshly revivified peroxide. Thereafter the solution of crude alum is introduced into tank A.

Following the third day of operation, the iron free alum solution in tank D is pumped to the iron free alum storage. The supernatant liquid in tank A is pumped into tank D, and the supernatant liquid in tank E is pumped to tank C, thereafter a crude alum solution is introduced into tank E. The spent peroxide contained in tank A is washed free of alum during the fourth day of operation and subjected to the early stages of revivification. The partially revivified peroxide of tank B is subjected to continued revivification and thereafter to the washing operation to remove the revivification liquors preparatory for the deferruginating cycle of the fifth day. At the end of the fourth day the iron free alum in tank C is pumped to the iron free alum storage. The supernatant liquid in tank D is pumped to tank B which contains fresh peroxide and the supernatant liquid in tank E is pumped to tank C.

The cycle of operation set forth above is exemplary of one method of procedure which involves a three stage cycle of deferrugination. Obviously, two, four or more stages may be employed. I found, however, that for the ordinary grade of crude alum, a three one-day-stage cycle is adequate and avoids aging of the alum. The above method of procedure contemplates an intermittent counter-current treatment of alum solution. Obviously, a continuous counter-current cycle in which the flow of alum solution is counter-current to the movement of the peroxide particles and in which the clear alum solution which is discharged immediately after

having been in contact with freshly revivified peroxide may be employed in lieu of the intermittent counter-current flow of the materials. An important feature in each instance is the same, namely, that the progressive stages of equilibria between the peroxide and the alum solution are such that the partially deferruginated alum reacts with the freshly revivified peroxide and the crude alum reacts with the partially spent peroxide.

To illustrate the results attainable by the present process, five tanks each of approximately 2000 cubic feet capacity and each charged with approximately 5700 pounds of peroxide are capable of deferruginating a crude basic alum ($17.3\% \text{ Al}_2\text{O}_3$) containing $.36\% \text{ Fe}_2\text{O}_3$ at the rate of 28.6 tons per day to produce a product containing $.0001\% - .0002\% \text{ Fe}_2\text{O}_3$. Even when the crude alum contains as much as $.5\% \text{ Fe}_2\text{O}_3$, the product will be found to contain well below the maximum limit of iron permissible in iron free alum.

An analysis of the alum solution at the end of the several stages of deferrugination indicates that the iron content varies substantially as follows:

	Percent Fe_2O_3
Crude alum	.360
1st stage	.152
2nd stage	.0095
3rd stage	.0002

To illustrate the advantages of a counter-current treatment, if one were to produce an alum solution containing $.0002\% \text{ Fe}_2\text{O}_3$ from a crude alum containing approximately $.36\% \text{ Fe}_2\text{O}_3$ in a single stage, it would require approximately 206,000 pounds of peroxide of a quality similar to that provided by the present invention and used in the foregoing example.

When it is remembered that a substantial amount of alum is not separable from the peroxide by decantation (in the afore-described three-stage procedure the peroxide contains approximately .45 pounds of alum per pound of peroxide at 20° C . after decantation) it will be apparent that it would be impractical to employ a single stage process since substantially all of the alum solution would be retained by the peroxide.

Even if one desired to produce an alum containing $.002\% \text{ Fe}_2\text{O}_3$ by a single-stage process one would require 25,800 pounds of PbO_2 to reduce the iron content from $.5\% \text{ Fe}_2\text{O}_3$ to $.002\% \text{ Fe}_2\text{O}_3$. In addition to the difficulties involved in handling such large amounts of peroxide one is also confronted with the problem of washing the peroxide with water to recover the entrained alum solution. Moreover, the dilute alum solution so obtained must be evaporated which is in itself a serious objection to the process and results in a substantial additional expense.

From the foregoing it is obvious that the Semper-Fahlberg process which involves the use of 5-20% of peroxide would be ineffective insofar as fulfilling the requirements of present day iron free alum specifications is concerned.

Figure 2 is representative of the equilibrium condition which exists between lead peroxide and an iron containing alum solution. From this chart it will be apparent that an alum solution containing approximately $.1\% \text{ Fe}_2\text{O}_3$ is in equilibrium with lead peroxide which contains approximately 3% of its weight of Fe_2O_3 adsorbed thereon. It will likewise be apparent that a

solution containing $.0001\% \text{ Fe}_2\text{O}_3$ is in equilibrium with a lead peroxide which contains approximately .3% Fe_2O_3 . Stated otherwise, in order to produce an alum which contains $.0001\% \text{ Fe}_2\text{O}_3$ the lead peroxide with which it is ultimately in equilibrium can contain no more than $.3\% \text{ Fe}_2\text{O}_3$ adsorbed on its surface.

In connection with the chart it is to be borne in mind that the amount of iron oxide adsorbed on the lead peroxide refers to the iron which is recoverable by a revivification treatment and not to the iron which would be indicated by an ultimate analysis. In other words, lead peroxide may contain some iron as an impurity which does not enter into the equilibrium reaction. It is also to be borne in mind that since the condition and history of the peroxide have an important effect on its capacity to adsorb iron the curve will vary, particularly with respect to its axis of abscissas, although its general contour will remain approximately the same.

The present process is adaptable to the removal of materials other than iron from alum. Thus, for example, an alum which contains arsenic, chromium, manganese, nickel or cobalt or mixtures of compounds of these metals may be treated in an analogous manner whereby their removal is effected as in the case of iron. In some instances the removal of these impurities appears not to involve an adsorption phenomenon. Moreover, some of the peroxide is lost or destroyed. The loss of peroxide suffered may be offset by the addition of an equivalent quantity of fresh peroxide.

Inasmuch as more iron can be tolerated in commercial alum than would normally be present when one reacts sulphuric acid with the commercial grade of bauxite, it is convenient to omit the washing operation whereby the alum solution is separated from the spent peroxide before revivifying with acid and to revivify the alum containing peroxide counter-currently with sulphuric acid. The acid together with the dissolved iron and alum solution associated with the spent peroxide may be utilized in the manufacture of ordinary commercial grade of alum.

The mechanical features of the operation are similar to those employed in deferruginating cycle. Thus, the partially spent sulphuric acid, which contains some iron is agitated with the peroxide whereby an equilibrium is established. The suspension is then permitted to settle and the supernatant liquid is pumped to the crude alum department. Thereafter the peroxide is agitated with a sulphuric acid solution which contains less iron than that employed in the next preceding revivification stage and which has been obtained as a supernatant liquid from the next preceding charge of peroxide undergoing revivification. The supernatant liquid which is obtained during this treatment is used in the first stage of revivification of a subsequent charge of spent peroxide. In all, seven such stages of revivification are employed, the final stage involving the use of a 6% aqueous solution of pure sulphuric acid. The resulting peroxide is finally washed, substantially free from sulphuric acid with water, after which it is ready for use in the deferruginating cycle corresponding to tank A at the beginning of the first day, as illustrated in the diagram.

The fresh acid solution gains in iron content with each successive treatment as indicated by the following results which have been obtained in the treatment of the spent peroxide resulting

from the three stage deferruginating operation described above:

	Percent Fe ₂ O ₃
Fresh acid	.010
5 Acid after 7th stage of peroxide revivification	.019
10 Acid after 6th stage of peroxide revivification	.022
15 Acid after 5th stage of peroxide revivification	.045
20 Acid after 4th stage of peroxide revivification	.075
25 Acid after 3rd stage of peroxide revivification	.210
30 Acid after 2nd stage of peroxide revivification	.365
35 Acid after 1st stage of peroxide revivification	.520

20 The revivification is likewise an intermittent counter-current treatment which takes advantage of the adsorption phenomenon involved in the present process. Obviously, a single revivification treatment may be employed. However such treatment would be grossly wasteful of sulphuric acid. Fewer treatments than seven may be employed by using a correspondingly greater quantity of acid in each treatment. Similarly, a greater number of treatments may be employed. The number of treatments will, of course depend upon the quantity of acid which can be utilized economically in the crude alum department.

35 A convenient procedure for effecting a seven stage revivification involves the use of seven tanks each of approximately 600 cubic foot capacity. Six may be assumed to be filled with acid solutions having differing percentages of iron dissolved therein. The seventh tank contains a freshly prepared 6% solution of sulphuric acid. For effecting the first stage of revivification of the spent peroxide, acid containing a maximum amount of iron is introduced and thoroughly mixed with the peroxide solution which by reason of imperfect decantation 40 contains some entrained alum solution. Such peroxide corresponds, for example, to that contained in tank D on the first day as represented in Figure 1. After sedimentation the supernatant liquid is decanted and transferred to the crude alum department where it may be admixed with fresh sulphuric acid and thereafter reacted with bauxite in the usual manner to form alum.

45 The next stage of revivification involves introducing and thoroughly mixing with the peroxide the acid contained in one of the seven storage tanks, the iron content thereof being less than that which was employed in the first stage but is greater than that in any of the other revivification liquor tanks. After sedimentation the supernatant liquid is pumped into one of the empty tanks where it is held preparatory for use in the first stage of revivification of the next succeeding charge of spent peroxide. For the next stage the peroxide is thoroughly mixed with an acid solution containing successively less iron than the next preceding. After sedimentation the supernatant liquid is pumped into one of the empty storage tanks and held in readiness for use in the treatment of the next succeeding batch of lead peroxide. This cycle is continued through the seventh stage in which fresh acid is employed.

50 It is to be noted that one may employ, in lieu

of the intermittent counter-current process a revivification which is continuous and which is characterized by the fact that the fresh acid contacts with partially revivified peroxide whereas the iron containing acid contacts with the spent peroxide, in the same manner as one may deferruginate an alum solution continuously.

55 From the foregoing description, it will be apparent that the present invention affords a convenient, economical and practical process for removing iron from alum which is characterized in that it consumes no non-recoverable materials, requires no expensive equipment or difficult operating conditions and enables one to manufacture large quantities of product of any 10 desired iron content with comparatively small investment costs. The invention contemplates a novel lead peroxide reagent and method of preparing the same, which is peculiarly adapted for effecting the objects of the invention. The 15 invention likewise affords a method of removing iron from basic alum as contrasted to the neutral or slightly acidic alum, and in this respect is of marked importance since by far the greatest consumption of alum is that of a basic nature. In addition, the invention includes a 20 convenient and economical method of regenerating a peroxide whereby no loss in materials is incurred and obviates the hazard of loss of alum by reason of aging of the iron present in an alum solution. Finally, by reason of the discovery of the principles involved, the invention affords a 25 method of procedure whereby a commercial practical output of iron free alum is made possible and an economical use of the peroxide reagent is realized.

30 Although the invention has been described in detail and various modifications have been indicated, it will be apparent to those skilled in the art that the invention is not so limited, but 35 is susceptible to numerous modifications without departing from the spirit thereof or the scope of the appended claims.

What I claim is:

1. The method of removing water soluble in- 45 organic ferric salts from an alum solution, which consists in treating a crude aqueous alum solution containing the iron, with lead peroxide whereby the iron is removed from the alum solution by the peroxide, said method being characterized in that the alum solution moves counter- 50 currently with respect to the peroxide in the course of the treatment.

2. The method of removing water soluble in- 55 organic ferric salts from an aqueous alum solution by means of lead peroxide characterized in that the alum solution is treated in successive stages during which the alum solution moves counter-currently with respect to the peroxide reagent, each stage involving the formation of 60 an intimate suspension of the peroxide in the alum solution and subsequent separation of the alum solution from the peroxide.

3. The method as defined in claim 2 and further characterized in that the separation of the peroxide is effected by sedimentation and decantation of the clear supernatant alum solution.

4. The method as defined in claim 2 and further characterized in that three stages of treatment are employed.

5. The method as defined in claim 2 and further characterized in that the alum treated is a basic aluminum sulphate.

6. In the manufacture of iron free alum the steps of treating an aqueous solution of alum 75

- with lead peroxide whereby the iron is removed from the solution by said peroxide, subsequently separating the spent peroxide from the alum solution, treating the peroxide mixture successively with dilute sulphuric acid, the acid of each successive treatment containing less iron, washing the resulting peroxide free from acid and finally returning the washed peroxide to the alum solution treating process.
10. 7. The method as defined in claim 6 and further characterized in that the peroxide is subjected to a counter-current revivification treatment wherein fresh acid moves counter-currently with respect to the peroxide undergoing revivification, whereby the fresh acid contacts the peroxide which is substantially free of iron and the spent acid contacts the peroxide containing a maximum of iron.
8. In the manufacture of iron free alum the steps of treating an aqueous solution of alum with lead peroxide whereby the iron is removed from the solution by said peroxide, subsequently separating the spent peroxide from the alum solution, treating the peroxide mixture with dilute sulphuric acid, whereby the iron contained in the peroxide is removed and the peroxide thus revivified, separating the acid solution from the peroxide, returning the revivified peroxide for reuse, and reacting the acid solution containing the iron and the sulphuric acid with bauxite.
9. In the removal of iron salts from an alum solution by means of lead peroxide, the step of rendering the iron susceptible to peroxide treatment, which consists in heating the alum solution to an elevated temperature not substantially above the normal boiling temperature thereof and subsequently cooling said solution.
10. The method of removing iron salts from

an alum solution by means of lead peroxide as defined in claim 12, and further characterized in that the suspension of the peroxide in the alum solution is maintained at a temperature of approximately 20°-50° C.

11. The method as defined in claim 12, and further characterized in that the concentration of the alum solution is not substantially in excess of 30° Bé.

12. A multistage counter-current process for the removal of water soluble iron salts from an alum solution, which involves agitating an alum solution with a lead peroxide reagent whereby a uniform suspension is obtained, and effecting sedimentation of the suspension, said process being characterized in that the fresh peroxide is treated with alum which is in its final stage of deferrugination and the crude alum solution is treated with a partially spent peroxide.

13. The method as defined in claim 12 and further characterized in that the alum solution is caused to undergo three successive stages of deferrugination counter-currently with respect to the peroxide reagent.

14. The method of removing water soluble inorganic ferric salts from an alum solution, which consists in treating a crude aqueous alum solution containing the iron, with lead peroxide whereby the iron is removed from the alum solution by the peroxide, said method being characterized in that the alum solution is contacted with the peroxide in successive stages and further characterized in that during the final stages of the treatment a peroxide is employed containing less iron than the peroxide employed in the initial stages of the treatment.

WILLIAM S. WILSON.
